CLAIM

I claim the ornamental design for a decorative base for a cane, walking stick, crutch, walker, and the like, as shown and described.

DESCRIPTION

FIG. 1 is a front perspective view of a decorative base for a cane, walking stick, crutch, walker and the like showing my new design;

FIG. 2 is a rear elevation view thereof.

FIG. 3 is a front elevation view thereof.

FIG. 4 is a left side elevation view thereof.

FIG. 5 is a right side elevation view thereof.

FIG. 6 is a top plan view thereof; and,

FIG. 7 is a bottom plan view thereof.

In the drawings, the broken lines shown in the Figures depict unclaimed subject matter only and form no part of the claimed design.
